(57) **CLAIM**

The ornamental design for a cover for mobile phone, as shown and described.

DESCRIPTION

FIG. 1 is a front perspective view of a cover for mobile phone showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof; and,
FIG. 8 is a perspective view of the cover for mobile phone in an open configuration showing the interior of the cover.
The broken line shown in FIGS. 3-7 represents a boundary of the claim wherein the portion of the rear surface between the broken line and the solid line (shown only in FIG. 3) immediately surrounding the opening forms no part of the claimed design.
